DESIGN FOR A SLACKS SUIT

Murray Kay, New York, N. Y.

Application March 10, 1942, Serial No. 106,128

Term of patent 7 years

To all whom it may concern:

Be it known that I, Murray Kay, a citizen of the United States of America, residing at 310 West 85th Street, city, county, and State of New York, have invented a new, original, and ornamental Design for a Slacks Suit, of which the following is a specification, reference being had to the accompanying drawing, forming part thereof.

In the drawing:

Fig. 1 is a front elevational view of a slacks suit showing my design with the blouse unbuttoned from the trousers;

Fig. 2 is an enlarged fragmentary rear view of the blouse portion of the slacks suit shown in Fig. 1; and

Fig. 3 is a fragmentary view of one of the leg portions of the slacks suit in fastened position.

The back of the slacks is conventionally plain, and the other half of the blouse back is the same as the half shown in Fig. 2.

I claim:

The ornamental design for a slacks suit, substantially as shown and described.

MURRAY KAY.
